Patented Apr. 12, 1927.

UNITED STATES PATENT OFFICE.

JAMES BECKWITH, OF EUGENE, OREGON.

CARBONIZED ARTICLE AND PROCESS OF MAKING SAME.

No Drawing.

Application filed August 18, 1924. Serial No. 732,729.

An object of the invention is the production of articles, specifically pipes, from clay, meerschaum or similar substances, which have the small interstices of the body there-
5 of wholly or partly filled with fine particles of carbon and are given a desired color ranging from light brown to intense black.

Another object of the invention is a process for making these articles by a simple 10 treatment in which they are produced as a by-product in the manufacture of charcoal or coke in pits.

A common manner of manufacturing charcoal in pits is to form a somewhat 15 frusto-conical pile of wood around a central pole having an opening around it. The sticks of wood are arranged in tiers and layers, the number of each depending upon the size of the pit, and over the outer layer 20 of wood is placed a layer of straw which in turn is covered with earth. The pit is fired in the center and takes about three weeks to burn.

In the preferred form of carrying out this 25 process, the articles of clay or meerschaum or similar substance, are placed underneath the outer layer of wood, and for convenience, at the top of the second tier, and are covered by this outer layer, the layer of straw and 30 the layer of earth. The exact location is immaterial except that they should be placed well toward the outside of the stack. So far as the invention is concerned, these 35 articles may be packed in any desired manner provided that the gases, smoke and volatile products may have ready access thereto. A very satisfactory manner of packing such 40 articles as pipes has been found to place them tightly in a box which is bored full of holes. This is merely for convenience, since a single article or a plurality thereof placed in the pit without any container will be properly treated.

When the pit is fired, the smoke, gases, 45 and volatile products driven off from the wood circulate through the layers and come in contact with the articles. For a long time, these are not raised to a very high heat, and certain of the volatile products may 50 condense and be absorbed by the articles. However, as the pit continues to burn, the temperature increases, and if the articles are left until the firing is completed, they will 55 ultimately be subjected to a temperature of about 1800 degrees F. Not only the volatile products which have been deposited on or

absorbed by the articles will be driven off, but any volatile elements of the material of the articles themselves will be driven off. Very fine particles of carbon will be de- 60 posited in the interstices of the body of the article and the clay or meerschaum will be hardened.

If the articles are allowed to remain during the entire firing of the pit they will be 65 an intense black. If removed earlier, lighter shades may be obtained. They will take a very high polish readily and break with difficulty. The exact character of the product will vary with the character of the mate- 70 rial employed, but in general a dark color, hardness, and capacity for a high polish are characteristic.

It is to be noted that the execution of this 75 process requires no special preparation of the article. Pipes of meerschaum or clay, or other articles of the same or similar materials are manufactured in the usual manner and then subjected to the treatment as de- 80 scribed. It is further to be noted that the process described requires no modification of the usual method of burning charcoal. The treatment of the articles can therefore be carried out as an incident to the usual charcoal burning. The treated articles may 85 be afterwards painted or colored or treated as desired. In the case of pipes, any desired type of mouthpiece may be provided.

While my invention relates broadly to articles of any desired type and the particular 90 process for treating the same, it is specifically adapted to pipes and more especially to meerschaum pipes. Meerschaum pipes thus treated have an appearance similar to those colored by long smoking and are rendered 95 very hard so that danger of breakage is small. Pipes of any material thus treated absorb nicotine less readily and do not become strong.

This application is closely related to ap- 100 plicant's copending case Patent No. 1,600,501 granted Sept. 21, 1926.

Various details may be modified without in any manner departing from the spirit of the invention which is to be regarded as 105 limited only by the scope of the appended claims.

I claim as my invention:

1. A process for the treatment of articles which comprises subjecting them for a relatively long period to the volatile products arising in the production of charcoal and 110

for a relatively short period to a temperature high enough to drive off volatile constituents from the articles and deposit fine particles of carbon in the interstices of the material of the articles.

2. As an article of manufacture, a meer-schaum pipe having finely divided carbon

deposited in the interstices of the meer-schaum, whereby the same is hardened, given a high color, and rendered susceptible ¹⁰ of taking a high polish.

In testimony whereof, I have hereunto subscribed my name.

JAMES BECKWITH.
